R. L. ASPDEN

FLYWHEEL DYNAMO ELECTRIC MACHINE FOR INTERNAL COMBUSTION ENGINES

Filed Dec. 19, 1923

*Inventor
R. L. Aspden
By Marks Clerk
Atys.*

UNITED STATES PATENT OFFICE.

RALPH LEONARD ASPDEN, OF CHORLEY, ENGLAND.

FLYWHEEL DYNAMO-ELECTRIC MACHINE FOR INTERNAL-COMBUSTION ENGINES.

Application filed December 19, 1923. Serial No. 681,649.

To all whom it may concern:

Be it known that I, RALPH LEONARD ASPDEN, a subject of the King of Great Britain and Ireland, and residing at 6 Southport Road, Chorley, in the county of Lancaster, England, have invented certain new and useful Improvements in and Relating to Flywheel Dynamo-Electric Machines for Internal-Combustion Engines, of which

10 the following is a specification.

The invention relates to fly-wheel dynamo-electric machines for use as starters and particularly to those of the kind invented by the present applicant and described in the 15 specifications of British Patents Nos. 153,721 and 187,665.

The primary object of the present invention is to simplify mechanisms of the kind indicated and render them more compact.

20 With such an object:—

The invention consists in a fly-wheel dynamo-electric machine of the kind indicated having an engine shaft, transmission shaft and rotary member of a dynamo-electric machine mounted as independently rotatable parts and a member of a three-piece clutch in rigid relation to one of said parts and adapted to be forced into operative engagement with a second of said parts by 30 the third part, operation of said third part acting both to clutch and declutch the three parts simultaneously.

The invention also consists in a device of the kind indicated in which the fly-wheel 35 comprises two coaxial clutch-carrying parts, one of which is attached to the engine shaft and the other to a rotary member of the dynamo-electric machine, the latter part being capable of axial movement.

40 The invention also consists in a device of the kind indicated in which the independently rotatable engine shaft, transmission shaft and rotary member of the dynamo-electric machine, by axial movement of such 45 rotary member, can be simultaneously clutched together, the clutching operation being effected by a single instrumentality, such as a pedal.

The invention further consists in a device 50 as indicated in which a part, preferably acting as a fly-wheel and secured to the essential rotary element of the dynamo-electric machine, acts as a presser for the clutch

operation referred to in the preceding paragraph. 55

The invention still further consists in a device of the kind indicated in which one element of a three-piece clutch attached to the transmission shaft is interposed between co-acting clutch members mounted respectively on the engine shaft and on a part connected to the rotary element of the dynamo-electric machine. 60

The invention finally consists in the improved fly-wheel dynamo-electric machines 65 hereinafter described.

The accompanying drawing shows as regards its upper half, a sectional elevation and as regards its lower half an outside elevation of one form of the invention, by 70 way of example.

According to this form of the invention, applied as a starter for an internal combustion motor driving, for example, a road vehicle, a disc, *a*, with a substantial rim, *b*, 75 acting as a fly-wheel, is mounted on the engine shaft, *c*, one side, *d*, of this rim being faced up to act as a clutch surface. In juxtaposition to the clutch surface, *d*, in question a plate, *e*, is arranged which is 80 mounted on the transmission shaft, *f*, i. e., the shaft leading to the gear-box; while one operative face, *h*, of the plate member, *e*, is in juxtaposition to the clutch face, *d*, on the rim as above described, the other operative face, *i*, of the plate member is in 85 similar juxtaposition with a face, *k*, formed on part of a sleeve member, *m*, acting as a fly-wheel, *m'*, and secured to the armature, *n*, of the dynamo-electric machine, the field 90 magnets, *o*, being secured to any suitable stationary part, such as the casing, *r*. The armature, *n*, is free to rotate on the sleeve, *s*, by virtue of the ball bearings, *t*, but is prevented from moving axially in relation to 95 the sleeve, *s*, by the collar, *u*. The armature, *n*, and fly-wheel, *m*, as a whole are carried on the transmission shaft, *f*, on which they can slide bodily in an axial direction. It will thus be seen that the engine 100 shaft, transmission shaft and armature are

rotatable independently in relation to one another. A helical spring, *v*, surrounding the transmission shaft acts normally by way of the Z-ring, *w*, ball thrust bearings, *x*, and 105 flange, *n'*, to press the armature, *n*, and con-

nected fly-wheel against the plate, *e*, attached to the transmission shaft, *f*, but by means of a flanged sleeve, *z*, slideable on the latter and operated from a single instrumentality such as the usual clutch pedal, 2, by way of a lever or fork, 3, and pin, 4, the armature may be moved longitudinally a short distance against the action of the spring to free the clutch surfaces, the thrust 10 in this case being taken by the ball bearings, 5.

The action of the device described is as follows:—

Assuming the clutch pedal, 2, operated to move the armature, *n*, against the action of the spring, *v*, it is then free to rotate and on switching in the battery quickly achieves a high rate of revolution, thereby storing considerable energy in the fly-wheel attachment, 20 *m'*. Upon releasing the pedal, the helical spring acts to force the armature and fly-wheel to the left as seen in the drawing, thereby gripping the plate, *e*, attached to the transmission shaft between the clutch 25 surfaces *k* and *d*, disposed respectively on the fly-wheel, *m'*, attached to the armature and the fly-wheel rim, *d*, attached to the engine shaft.

By this operation it will be seen that the 30 engine is simultaneously clutched both to the transmission shaft and to the dynamo. The change-speed gear being in the neutral position, the parts indicated rotate as one and the motor is thus started.

In a similar manner the motor is simultaneously declutched from the dynamo and the transmission shaft.

In some cases, if desired, the rotary part 40 of the armature may be constituted by the field magnets, the armature being stationary.

Although the preferred form of the present invention has been described above in which a single plate clutch is used, nevertheless in some cases a multiple plate clutch 45 or any other form of clutch suitable for the purposes in question may be used, the scope of the invention being wide enough to include other alterations in the form and general arrangement of the parts so long as no 50 departure is made from the principles of operation set forth in an earlier part of this specification.

Having now described my invention, what I claim as new and desire to secure by Letters Patent is:—

1. A device of the kind indicated having an engine shaft and a co-axial transmission shaft and rotary member of a dynamo-electric machine mounted as independently rotatable elements, and force-transmitting means severally mounted on said rotatable parts, the force-transmitting means mounted on said transmission shaft being interposed between the force-transmitting means mounted on said engine shaft and rotary member, together with a single instrumentality for bringing all said force-transmitting means into operative relation, as set forth. 55

2. A device of the kind indicated having an engine shaft, transmission shaft and rotary member of a dynamo-electric machine mounted as independently rotatable parts, force-transmitting means severally mounted on said rotatable parts and means for gripping said force-transmitting means mounted on said transmission shaft between said force-transmitting means mounted on said engine shaft and rotary member, as set forth. 60

3. A device of the kind indicated having an engine shaft, transmission shaft and rotary member of a dynamo-electric machine mounted as independently rotatable parts, said engine shaft and rotary member each having a clutch face and said transmission shaft having a pair of clutch faces to contact respectively with said other clutch faces, together with means for axially moving said rotary member to clutch and declutch 85 said three rotatable parts simultaneously, as set forth. 80

4. A device as claimed in claim 1, in which said rotary member is freely rotatable on and movable axially in relation to said transmission shaft, as set forth. 95

5. A device as claimed in claim 1, in which said transmission shaft carries a disc on which is mounted the force-transmitting means proper, as set forth. 100

In testimony whereof I have signed my name to this specification.

RALPH LEONARD ASPDEN.
